WILLIAM MORRIS GRISCOM, OF READING, PENNSYLVANIA, ASSIGNOR TO
HARBSTER BROTHERS & CO., OF SAME PLACE.

Design No. 4,475, dated November 15, 1870.

DESIGN FOR A SAD-IRON.

The Schedule referred to in these Letters Patent and making part of the same.

I, WILLIAM MORRIS GRISCOM, of Reading, county of Berks, State of Pennsylvania, have invented or produced a Design for a Sad-Iron, of which the following is a specification.

On reference to the accompanying drawing—
Figure 1 is a side view of a sad-iron made in accordance with my design; and

Figure 2, a perspective view of the same, showing a more elaborate ornamentation of the handle.

The general outline of the body A of the iron is the same as usual; that is, it is square at the back, and has curved sides meeting at a point in front.

The edge of this portion of the iron is ornamented by a molding, consisting of an outwardly-projecting curve, *a*, above and below which are beadings or shoulders *b* and *b'*, the latter projecting upward at the front of the iron, as shown at *x* in the drawing.

The handle B of the iron is of the peculiar form represented, and may be perfectly plain, as shown in fig. 1, or it may be ornamented, as illustrated in fig. 2, or otherwise.

Claims.

1. The design for a sad-iron, substantially as described, and as represented in fig. 1 of the drawing.

2. The same when ornamented, substantially as represented in fig. 2 of the drawing.

In testimony whereof, I have signed my name to this specification in the presence of two subscribing witnesses.

WILLIAM MORRIS GRISCOM.
